UNITED STATES PATENT OFFICE

2,602,662

MECHANICAL MOVEMENT

Warren H. Kintzinger, Cedar Rapids, Iowa

Application November 23, 1945, Serial No. 630,336

7 Claims. (Cl. 267—1)

1

This invention relates to improvements in mechanical movements.

An object of this invention is to provide an improved mechanical movement wherein a plunger is slideable in a casing throughout a range of movement, wherein a spring force may be applied to the plunger for advancing the same throughout a portion of the range of movement and wherein the plunger is free of the spring force throughout the remaining portion of the range of movement when it has been retracted to that remaining portion.

A further object of this invention is to provide an additional spring force to the plunger which is effective at least through said remaining portion of the range of movement to advance the plunger.

Another object of this invention is to provide an improved mechanical movement of the type specified above but wherein a plurality of spring forces may be sequentially applied to the plunger to advance the same with varying amounts of force during its advancing movement.

Still another object of this invention is to provide an improved mechanical movement, of the type specified above but wherein a spring force may be applied to the plunger to move it in one direction from an intermediate position, wherein a spring force may be applied to the plunger to move it in the opposite direction from another intermediate position and wherein the plunger is free with respect to said spring forces between said intermediate positions.

A further object is to provide means in the mechanical movements of the type specified above wherein the application of the spring force to the plunger may be readily prevented.

The mechanical movements of this invention have numerous uses and may be readily utilized for such purposes as door springs, door checks, car springs, shock absorbers and for many other purposes requiring the above spring force actions.

Other objects and advantages will become apparent to those skilled in the art upon reference to the accompanying specifications, claims and drawings in which:

Figure 1 is a sectional view of one form of this invention showing the plunger retracted;

Figure 2 is a view similar to Figure 1 showing the plunger advanced;

Figure 3 is a sectional view taken substantially along the line 3—3 of Figure 2;

Figure 4 is a sectional view of another form of the invention showing the plunger retracted;

Figure 5 is a view similar to Figure 4 but showing the plunger advanced;

5

Figure 6 is a sectional view of another form of this invention wherein the spring force is applied in opposite directions, the plunger being shown in an intermediate position;

5

Figure 7 is a sectional view taken substantially along the line 7—7 of Figure 6;

Figure 8 is a view similar to Figure 6 but showing the plunger in the right hand position;

10

Figure 9 is a view similar to Figure 6 but showing the plunger in the left hand position;

15

Figure 10 is a sectional view of another form of this invention utilizing a plurality of springs for sequentially advancing the plunger, the plunger being shown in the retracted position;

15

Figure 11 is a view similar to Figure 10 but showing the plunger in the advanced position;

20

Figure 12 is a sectional view of a further form of this invention corresponding generally to the form illustrated in Figures 4 and 5; and

20

Figure 13 is a sectional view taken substantially along the line 13—13 of Figure 12.

25

Referring first to Figures 1 to 3, the mechanical movement device includes a casing unit 10 having a head 11 and an elongated cylindrical cup 12. The cup 12 may be screw threaded to the head 11 as at 13. The casing member 10 may be provided with a suitable bracket 14 with a hole 15 therein for purposes of mounting the casing member 10.

30

A plunger 16 is slidably mounted in the casing member 10 through a suitable bore in the head 11. The plunger 16 may be provided at its extremity with a suitable hole 17 for the purpose of mounting the plunger 16. The plunger is provided with a longitudinally extending groove 18 in which is located a pin 19 carried by the head 11. The groove 18 and the pin 19 operate to prevent rotation of the plunger 16 with respect to the casing 10.

35

The casing 10 is provided with a plurality of circumferentially spaced longitudinal grooves 21, four of such grooves being shown for purposes of illustration. The plunger 16 is provided with a plurality of longitudinal grooves 22 which are in circumferential register with the longitudinal grooves 21 of the casing 10. A plurality of arms 23 are located within the grooves 21 and 22 and are adapted to slide from the grooves 21 to the grooves 22 when the plunger 16 is advanced and

40

to slide from the grooves 22 to the grooves 21 when the plunger is retracted. As shown in Figure 1, the arms 23 are in the grooves 21, while in Figure 2 the arms 23 are in the grooves 22.

45

An actuator 25 is slidably mounted within the cup member 12 of the casing 10, and it includes an enlarged circular groove 26 for receiving the

ends of the arms 23. The actuator 25 is also provided with a bore 27 through which the plunger 16 may pass. The actuator 25 is also provided with a spring seat 28 which receives one end of a compression spring 29, the other end of the spring being accommodated in a stationary spring seat 30.

With the parts in the position shown in Figure 1, the plunger 16 is retracted, the spring 29 is compressed and the spring is acting to advance the arms 23. Advancing movement of the arms 23, however, is prevented because they are confined in the grooves 21 of the casing. The plunger 16 is, therefore, free to move with respect to the spring force provided by the spring 29.

As the plunger 16 is advanced by some external force, it moves to a position wherein the ends of the grooves 22 in the plunger line up with the ends of the arms 23. When this occurs, the compression spring 29 forces the arms 23 to slide from the grooves 21 into the grooves 22 with the result that the spring force is applied through the arms 23 to the plunger 16, whereby the spring 29 then advances the plunger 26 to the extreme right hand position shown in Figure 2.

When the plunger 16 is retracted by some external force, the initial retraction is opposed by the compression spring 29 acting through the arms 23. When, however, the plunger 16 is retracted to a position wherein the arms 23 line up with the grooves 21, further retracting of the plunger 16 causes the arms 23 to slide from the grooves 22 into the grooves 21. Further retracting movement of the plunger 16 is therefore free with respect to the spring force of the spring 29.

Therefore, the plunger 16 is free with respect to the spring 29 throughout a portion of its total range of movement, and when the plunger 16 is advanced beyond this portion of the range of movement, then the spring 29 becomes effective to move the plunger 16 through the other portion of its complete range of movement.

The other form of the invention illustrated in Figures 4 and 5 utilizes all of the parts utilized in the form illustrated in Figures 1 to 3 and like reference characters have been utilized for like parts. In the form of the invention illustrated in Figures 4 and 5, the plunger 16 is provided with an internal bore 32 for slidably receiving a guide pin 33 suitably secured to the casing 10 as by screw threads 34. A coil spring 35 extends between the end of the casing 10 and the end of the plunger 16, and the spring 35 operates to advance the plunger 16 to the right. Thus the spring 35 imparts an advancing movement to the plunger 16 when the plunger is free with respect to the spring 29. If desired, the spring 35 may be of such length and configuration that it operates on the plunger 16 only so long as the plunger 16 is free with respect to the spring force imparted by the spring 29. On the other hand, the spring 35 may be of such length and configuration so that it at all times imparts an advancing movement to the plunger 16. The spring 35 may be lighter than the spring 29, thereby imparting less force to the plunger 16. The plunger 16 is, therefore, advanced through at least a portion of its range of movement by the light spring 35 and is advanced through the remaining portion of its range of movement by the heavy spring 29 alone or in combination with the light spring 35.

In the form of the invention shown in Figures 6 to 9, the plunger is adapted to be moved by

spring means in one direction from an intermediate position and in the opposite direction from another intermediate position, the plunger being free with respect to the spring means between the intermediate positions. In this form of the invention, the casing 40 includes a cylinder 41 and heads 42 and 43. The heads may be provided with lugs 44 and 45, respectively, which in turn are provided with holes 46 and 47 respectively for purposes of mounting the casing 40. The heads 42 and 43 may be screwed into the cylinder 41 as at 48 and 49, respectively. The plunger 50 extends through the casing member 40 and is slidably carried in bores in the heads 42 and 43. The plunger 50 includes a longitudinally extending groove 51 in which is located a pin 52 carried by the head 42. The groove 51 and the pin 52 operate to prevent rotation of the plunger 50 with respect to the casing 40.

The head 42 of the casing 40 is provided with a plurality of circumferentially spaced longitudinal grooves 53, three being shown for purposes of illustration. In a like manner, the head 43 is provided with a plurality of circumferentially spaced longitudinal grooves 54 and the grooves 53 and 54 are in longitudinal alignment with respect to each other. The plunger 50 is also provided with a plurality of circumferentially spaced grooves 55 which are in circumferential register with the grooves 53 and 54. A plurality of arms 56 operate in the grooves 53 and 55 and slide from the grooves 53 to the grooves 55 when the plunger 50 is moved to the right, as shown in Figure 8, and are adapted to slide from the grooves 55 into the grooves 53 when the plunger is moved to intermediate position, as shown in Figure 6, or to the left, as shown in Figure 9. A plurality of arms 57 are carried in the grooves 54 and 55 and are adapted to slide from the grooves 54 into the grooves 55 when the plunger 50 is moved to the left, as shown in Figure 9, and are adapted to move from the grooves 55 into the grooves 54 when the plunger is moved to intermediate position, as shown in Figure 6, or is moved to the right position, as shown in Figure 8.

An actuator 59 slidably mounted in the casing 40 has an annular groove 60 for receiving the ends of the arms 56, and it is provided with a bore 61 through which the plunger 50 extends. Another actuator 62 is provided with an annular groove 63 receiving the ends of the arms 57 and it is provided with a bore 64 through which the plunger 50 extends. A compression spring 65 extends between the actuators 59 and 62, it being accommodated in the actuator 59 by a spring seat 66 and in the actuator 62 by a spring seat 67.

With the parts in the position shown in Figure 6, the plunger 50 is in an intermediate position and the arms 56 and 57 are located in the grooves 53 and 54, respectively, the spring 65 is compressed and the plunger 50 is free to move with respect to the spring force of the spring 65.

When the plunger 50 is moved to the right, it moves freely until such time as the grooves 55 line up with the ends of the arms 56, and at this time the spring 65 causes the arms 56 to slide from the grooves 53 into the grooves 55, whereupon the spring 65 moves the plunger 50 toward the right to the position shown in Figure 8.

When the plunger 50 is moved to the left from the position shown in Figure 8, such movement is opposed by the spring 65, but when the plunger 50 reaches a position wherein the arms 56 line up with the grooves 53, then further movement

of the plunger 50 causes the arms 56 to slide from the grooves 55 into the grooves 53. At this point, therefore, the spring 65 is completely compressed, and the plunger 50 is free to move with respect to the force of the spring 65. As the plunger 50 is further moved to the left, it passes through the position shown in Figure 6 and reaches a position wherein the grooves 55 line up with the ends of the arms 57.

When this occurs, the spring 65 causes the arms 57 to slide from the grooves 54 into the grooves 55 whereupon the spring 65 operates to move the plunger 50 to the left to the position shown in Figure 9.

When the plunger 50 is moved to the right from the position shown in Figure 9, its movement is opposed by the spring 65, and when it has moved to a point wherein the arms 57 line up with the grooves 54, further movement of the plunger 50 beyond this point causes the arms 57 to slide from the grooves 55 to the grooves 54. When this occurs, the spring 65 is compressed, and the plunger 50 is free to move with respect to the spring force of the spring 65.

Therefore, in the form of the invention illustrated by Figures 6 to 9 the spring force operates to move the plunger in one direction from an intermediate point and in the opposite direction from another intermediate point, and the plunger is free to move with respect to the spring force between the intermediate positions.

In the form of the invention shown in Figures 10 and 11, a plurality of spring forces are sequentially applied during the advancing movement of the plunger for advancing the plunger with varying degrees of spring force. Here the casing 70 includes a head 71 and an elongated cup portion 72 screw threaded to the head 71 as at 73. The casing 72 may be provided with a lug 74 having a hole 75 for the purpose of mounting the casing. Located within the casing 70 is a partition 76 which is held stationary within the casing 70 by a pin 77.

A plunger 79 is slidably mounted in the casing 70 and is supported for sliding movement by bores in the head 71 and the partition 76. The plunger 79 may be provided with a suitable mounting structure, not shown. The plunger 79 is provided with a longitudinally extending groove 80 cooperating with a pin 81 carried by the head 71 for preventing rotation of the plunger 79 with respect to the casing 70.

The head 71 of the casing 70 is provided with a plurality of circumferentially spaced longitudinal grooves 83, and the plunger 79 is provided with a plurality of circumferentially spaced longitudinal grooves 84 which are in circumferential register with the grooves 83. A plurality of arms 85 are adapted to slide from the grooves 83 into the grooves 84 and vice versa. An actuator 86 is slidably mounted in the casing 70 and is provided with an annular groove 87 for receiving the ends of the arms 85. The actuator 86 is also provided with a bore 88 through which the plunger 79 extends. The actuator 86 in addition is provided with a spring seat 89 for accommodating one end of a compression spring 90, the other end being accommodated by a spring seat 91 in the partition 76.

The partition 76 is provided with a plurality of circumferentially spaced longitudinal grooves 93 and the plunger 79 is also provided with a plurality of circumferentially spaced longitudinal grooves 94 in circumferential register with the grooves 93. A plurality of arms 95 are adapted

to slide from the grooves 93 into the grooves 94 and vice versa. An actuator 96 is slidably mounted in the casing 70 and is provided with an annular groove 97 for receiving the ends of the arms 95. A bore 98 in the actuator 96 permits the plunger 79 to extend through the actuator 96. The actuator 96 includes a spring seat 99 for receiving one end of a compression spring 100, the other end of which is accommodated by a spring seat 101 on the casing 70.

With the parts in the position shown in Figure 10, the plunger 79 is completely retracted, the arms 85 are in the grooves 83, the arms 95 are in the grooves 93 and the springs 90 and 100 are compressed. The plunger is free to move with respect to the spring forces of the springs 90 and 100.

As the plunger is advanced to the right from the position shown in Figure 10, the grooves 84 line up with the ends of the arms 85 whereupon the spring 90 causes the arms 85 to slide into the grooves 84 to impart a spring force to the plunger 79 for advancing the same.

As the plunger 79 continues in its advancing movement, the grooves 94 line up with the arms 95 and the spring 100 then causes the arms 95 to slide into the grooves 94 whereupon the spring 100 imparts a spring force to the plunger 79 for further advancing the plunger with a further force to the position shown in Figure 11.

When the plunger 79 is retracted from the position shown in Figure 11, the retraction is opposed by both springs 100 and 90. When in its retraction movement, the plunger 79 reaches a position wherein the arms 95 line up with the grooves 93, the arms 95 slide into the grooves 93 and the spring 100 is compressed and the plunger 79 is free to move with respect to the spring force of the spring 100. Further retracting movement of the plunger 79 is opposed then only by the spring 90, and when the plunger 79 is moved to a position wherein the arms 85 line up with the grooves 83, the arms 85 slide into the grooves 83. At this point then the spring 90 is compressed and the plunger 79 is free to move with respect to the spring force of the spring 90. Further retracting movement of the plunger 79 is therefore free until it reaches the retracted position, as shown in Figure 10.

Accordingly the form of the invention shown in Figures 10 and 11 permits free advancing movement of the plunger 79 through a portion of its range of movement, causes the plunger to be advanced by a spring force through another portion of its range of movement and causes the plunger to be advanced by an additional spring force through still another portion of its range of movement. When the plunger is being retracted, it is initially opposed by two spring forces. Then it is opposed by a single spring force and then it is free to move with respect to the spring forces.

The form of the invention shown in Figures 12 and 13 is very similar to that in the form illustrated in Figures 4 and 5 and like reference characters for like parts have been utilized. In the form illustrated in Figures 12 and 13, however, the circumferentially spaced longitudinal grooves 21 instead of being located in the head 11 are located in a sleeve 110 rotatably mounted in the casing 10. The sleeve 110 is provided with a handle 111 which moves through a slot 112 in the cup portion 12 of the casing 10. The slot 112 cooperating with the handle 111 limits the amount of rotation that may be applied to the

sleeve 110 and also prevents longitudinal movement of the sleeve 110.

With the parts in the positions shown in Figures 12 and 13, the grooves 21 and arms 23 are in circumferential register with the grooves 22 in the plunger 16 so that when the plunger 16 is advanced and retracted, the operation of this form of the invention is the same as that of the form illustrated in Figures 4 and 5.

When, however, the sleeve 110 is rotated to the other position, the grooves 21 and arms 23 are moved out of circumferential register with the grooves 22 in the plunger 16 so that as the plunger 16 is advanced, the arms 23 cannot slide into the grooves 22 whereby application of the spring force of the spring 29 to the plunger 16 is prevented. This arrangement, therefore, permits complete free movement of the plunger 16 with respect to the spring force of the spring 29 throughout its complete range of movement upon rotation of the sleeve to one position and permits free movement of the plunger with respect to the spring force of the spring 29 throughout only a portion of its range of movement when the sleeve 110 is rotated to the other position. Obviously, the rotatable sleeve arrangement of Figures 12 and 13 may be equally as well applied to the various forms of the invention illustrated herein.

I claim as my invention:

1. A mechanical movement comprising, a casing, a plunger slidable therein, a longitudinal groove of limited length in the plunger, a longitudinal groove of limited length in the casing in register with the groove in the plunger, an arm 35 slideable from one groove to the other as the plunger is advanced and retracted in the casing, spring means for advancing the arm, said spring means acting through the arm to advance the plunger when the arm slides out of the groove in the casing into the groove in the plunger and said spring means being compressed and said plunger being free of the spring means when the plunger is retracted and the arm slides out of the groove in the plunger into the groove in the casing.

2. A mechanical movement comprising, a casing, a plunger slidable therein, a longitudinal groove of limited length in the plunger, a longitudinal groove of limited length in the casing in register with the groove in the plunger, an arm slideable from one groove to the other as the plunger is advanced and retracted in the casing, spring means for advancing the arm, said spring means acting through the arm to advance the plunger when the arm slides out of the groove in the casing into the groove in the plunger and said spring means being compressed and said plunger being free of the spring means when the plunger is retracted and the arm slides out of the groove in the plunger into the groove in the casing, and second spring means acting on said plunger tending to move said plunger at all times.

3. A mechanical movement comprising, a casing, a plunger slidable therein, a longitudinal groove of limited length in the plunger, a longitudinal groove of limited length in the casing in register with the groove in the plunger, an arm slideable from one groove to the other as the plunger is advanced and retracted in the casing, spring means for advancing the arm, said spring means acting through the arm to advance the plunger when the arm slides out of the groove in the casing into the groove in the plunger and

5 said spring means being compressed and said plunger being free of the spring means when the plunger is retracted and the arm slides out of the groove in the plunger into the groove in the casing, and second spring means engaging said plunger and tending to advance said plunger at all times.

4. A mechanical movement comprising, a casing, a plunger slidable therein, a longitudinal groove of limited length in the plunger, a pair of spaced longitudinal grooves of limited length in the casing in register with the groove in the plunger, a first arm slideable from one of the grooves in the casing to the groove in the plunger when the plunger is moved in one direction in the casing, a second arm slideable from the other groove in the casing to the groove in the plunger when the plunger is moved in the other direction in the casing, spring means interposed between the arms, said spring means acting through one of the arms when that arm slides out of the groove in the casing into the groove in the plunger for moving the plunger in one direction, said spring means acting through the other arm when that arm slides out of the groove in the casing into the groove in the plunger for moving the plunger in the other direction, and said spring means being compressed and said plunger being free of the spring means when both arms 30 slide out of the groove in the plunger into the grooves in the casing.

5. A mechanical movement comprising a casing, a plunger slidable therein, first and second longitudinal grooves of limited length in the plunger, first and second longitudinal grooves of limited length in the casing in register respectively with the first and second longitudinal grooves in the plunger, a first arm slideable from the first groove in the casing into the first groove in the plunger when the plunger is advanced, a second arm slideable from the second groove in the casing into the second groove in the plunger when the plunger is advanced, first spring means for advancing the first arm, second spring means for advancing the second arm, said first spring means acting through the first arm to advance the plunger when the first arm slides out of the first groove in the casing into the first groove in the plunger and said first spring means being compressed and said plunger being free of the first spring means when the plunger is retracted and the first arm slides out of the first groove in the plunger into the first groove in the casing, said second spring means acting through the second arm to advance the plunger when the second arm slides out of the second groove in the casing into the second groove in the plunger and said second spring means being compressed and said plunger being free of the second spring means when the plunger is retracted and the second arm slides out of the second groove in the plunger into the second groove in the casing.

6. A mechanical movement comprising, a casing, a plunger slidable therein, first and second longitudinal grooves of limited length in the plunger, first and second longitudinal grooves of limited length in the casing in register respectively with the first and second longitudinal grooves in the plunger, a first arm slideable from the first groove in the casing into the first groove in the plunger when the plunger is advanced, a second arm slideable from the second groove in the casing into the second groove in the plunger when the plunger is advanced, first spring means for advancing the first arm, second spring means

for advancing the second arm, said first spring means acting through the first arm to advance the plunger when the first arm slides out of the first groove in the casing into the first groove in the plunger and said first spring means being compressed and said plunger being free of the first spring means when the plunger is retracted and the first arm slides out of the first groove in the plunger into the first groove in the casing, said second spring means acting through the second arm to advance the plunger when the second arm slides out of the second groove in the casing with the second groove in the plunger and said second spring means being compressed and said plunger being free of the second spring means when the plunger is retracted and the second arm slides out of the second groove in the plunger into the second groove in the casing, the longitudinal spacing of the first grooves being such with respect to the longitudinal spacing of the 20 second grooves that the first spring means becomes effective to advance the plunger sooner than the second spring means as the plunger is advanced.

7. A mechanical movement comprising, a 25 casing, a plunger slidable therein, a longitudinal groove of limited length in the plunger, a longitudinal groove of limited length in the casing in register with the groove in the plunger, an

arm slideable from one groove to the other as the plunger is advanced and retracted in the casing, spring means for advancing the arm, said spring means acting through the arm to advance the plunger when the arm slides out of the groove in the casing into the groove in the plunger and said spring means being compressed and said plunger being free of the spring means when the plunger is retracted and the arm slides out of the groove in the plunger into the groove in the casing, and means to shift the grooves with respect to each other to prevent sliding of the arm from one groove to the other.
